ATTORNEY.

UNITED STATES PATENT OFFICE.

FRANK W. GARRETT, OF JOHNSTOWN, PENNSYLVANIA, ASSIGNOR TO THE LORAIN STEEL COMPANY, OF PENNSYLVANIA.

CONTROLLER FOR ELECTRIC MOTORS.

SPECIFICATION forming part of Letters Patent No. 665,087, dated January 1, 1901.

Application filed September 25, 1900. Serial No. 31,068. (No model.)

To all whom it may concern:

Be it known that I, FRANK W. GARRETT, of Johnstown, in the county of Cambria and State of Pennsylvania, have invented a new and useful Improvement in Controllers for Electric Motors, of which the following is a full, clear, and exact description, reference being had to the accompanying drawings, which form a part of this specification.

My invention has relation to controllers for electric motors, and is designed to provide means of simple and effective character for preventing improper operation of the reverse-switches thereof.

With this object in view my invention consists in the combination, with a reverse-switch and its operating-handle, of a guard-plate adjacent to said handle and means for bringing together and separating said guard-plate and handle at predetermined times, said handle and plate being so constructed and arranged relatively to each other that when brought together the handle cannot be grasped for practical operation.

My invention further consists in means whereby the separation of the guard-plate and handle is made dependent upon the position of the regulating-switch of the controller, whereby such separation occurs only when the regulating-switch is at its off or open-circuit position.

My invention also consists in the novel construction and combination of parts, all as hereinafter described, and pointed out in the appended claims.

In the accompanying drawings, Figure 1 is a plan view of a controller embodying my invention. Fig. 2 is a vertical section on the line 2 2 of Fig. 1, and Fig. 3 is a section on the line 3 3 of Fig. 1.

In the figures the letter A designates the top of the controller-casing, B the shaft of the regulating-switch, and C the shaft of the reversing-switch.

D is the handle for the regulating-switch, and E is the handle of the reversing-switch.

F is a sleeve which is placed on the upper portion of the shaft C to rotate therewith, but to move loosely thereon in a vertical direction. This sleeve extends up through an aperture a in the controller-top and is formed

with a reduced cylindric extension f, which is removably engaged by the socketed hub of the handle E. Said sleeve is also formed with an inverted - cup - like flange f', which fits loosely over a boss a', surrounding the aperture, and forms a water-guard.

G is a lever pivoted at g to a suitable fixed support, which in the present instance is an extension H' of the bearing H for the reverse-switch shaft C. One arm of this lever carries an antifriction-roller g', which is arranged to be impinged by a cam I, carried by the shaft B of the regulating-switch. The other arm of said lever is forked to embrace the sleeve F, a groove f' of which is engaged by pins or studs i of the lever-forks.

J is a spring arranged to act on the lever G in opposition to the cam I.

K is a segmental plate or table underneath the handle E of sufficient circular extent to include the entire range of movement of the handle and of a radius equal to the length of the handle. This table is raised somewhat above the controller-top, with which it may be integrally cast, and has a central opening k to receive the hub portion of the handle, the latter having a circular flange E', which normally fits within and closes the said opening.

The handle E consists of a short comparatively thin piece having a flat under surface adapted to lie closely on the surface of the plate or platform K and an upper surface of oval convex form. When lying flat upon the table or platform K, it is therefore practically impossible for it to be grasped with sufficient force to enable the reverse-switch to be operated, and it remains in this position at all times save when the regulating-switch is moved to off position, when it is automatically raised sufficiently away from said table or platform to enable it to be easily grasped by the hand, this being effected by the action of the cam I and lever G, the latter being actuated by the former to raise the sleeve F. As soon as the handle D is moved from the off position the cam I ceases to act on said lever, and the sleeve F and handle are returned to normal position by the spring J, assisted by gravity.

When the handle is in its raised position, a flange F' on the sleeve F takes the place of the flange E' and closes the opening

k. E² is a lug on the hub portion E', whereby said handle is prevented from being removed when in its raised position unless the reverse-switch is first moved to off position, at 5 which position removal is permitted by reason of a slot k' in the table or platform K. Said lug passes through a slot in the flange F' and by its engagement with the walls of this slot forms the operative connection between said 10 handle and sleeve.

It is obvious that many changes in detail may be made without affecting the spirit and scope of my invention as set forth in the appended claims. Various mechanical devices 15 may, for instance, be used to impart vertical movement to the sleeve and handle, or the same may be effected electromagnetically, or the handle may be stationary and the guard-plate or platform be moved vertically into 20 and out of contact therewith, if desired. Hence I do not wish to limit myself to the particular construction, arrangement, and combination of parts which I have herein shown and described. I do not, however, 25 claim broadly, means for preventing operative access to the handle of the reversing-switch unless the regulating-switch is in a predetermined position, as I believe that to be the invention of George H. Parmelee, of Johnstown, Pennsylvania, as described and claimed 30 in his pending application, Serial No. 24,782, filed July 25, 1900.

Having thus described my invention, what I claim, and desire to secure by Letters Patent, is—

1. In an electric switch, the combination of a switch-handle, a guard-plate adjacent to said handle, and means for bringing together and separating the handle and plate, said 40 handle and plate being so arranged relatively that when brought together, the handle cannot be grasped for practical operation.

2. In an electric switch, the combination of a switch-handle, a guard-plate adjacent to 45 said handle, and means for bringing together and separating the handle and plate, said handle being shaped so that when the handle and plate are brought together, the handle cannot be grasped for practical operation.

50 3. In an electric switch, the combination of a switch-handle, a guard-plate underneath the said handle, and means for moving said handle into and out of engagement with the said plate, said handle and plate being relatively arranged to prevent the handle being grasped for practical operation when in engagement with the said plate.

4. In an electric switch, the combination with a guard-plate, of a comparatively thin 60 and flat switch-handle arranged to lie closely to the surface of said plate, and means for effecting a separation of said handle and plate under predetermined conditions.

5. In a controller for electric motors, the 65 combination with a guard-plate, of a switch-handle arranged to lie closely to and project but slightly from the surface of the said plate

and means for effecting a separation of said handle and plate.

6. In a controller for electric motors, the 70 combination of a regulating-switch, a reverse-switch, a handle for the reverse-switch, a guard-plate underneath the said handle, and means for moving said handle toward and away from said plate controlled by the 75 regulating-switch, said handle and plate being shaped and arranged relatively to each other to prevent the handle from being operatively grasped when in its nearest position to said plate.

80 7. In a controller for electric motors, the combination of a regulating-switch, a reverse-switch, a vertically-movable handle for the reverse-switch, a guard-plate underneath said handle, means for holding said handle normally in close relation to said guard-plate, and means controlled by the regulating-switch for effecting the separation of said handle and plate.

85 8. In a controller for electric motors, the 90 combination of a regulating-switch, a reverse-switch, a vertically-movable sleeve on the shaft of the reverse-switch, having a seat for an operating-handle, a handle detachably engaging the said sleeve, and movable therewith, a guard-plate underneath said handle, and means for raising and lowering the said 95 sleeve controlled by the regulating-switch, said handle and plate being shaped and arranged to prevent practical operative grasp 100 of the handle when in certain relation to each other.

9. In a controller for electric motors, the combination with the controller-easing, and the regulating and reversing switches mounted 105 therein, of the raised guard-plate or platform on the top of said easing around the reversing-switch shaft, the vertically-movable sleeve on the said shaft, the handle having a detachable engagement with said sleeve, and 110 constructed and arranged in one position of said sleeve to lie closely to the surface of the said plate, and means for actuating the said sleeve.

115 10. In a controller, the combination with 115 the regulating and reverse switches, and the casing therefor having an opening at its top around the reverse-switch shaft, a raised boss around the said opening, and also a raised platform or plate above and around the said 120 boss, said platform having an opening over the said opening in the casing, of the vertically-movable sleeve on the reverse-switch shaft having a seat for an operating-handle, and also a flange arranged to fit over the said 125 boss and also to close the opening in the said platform.

11. In a controller for electric motors, the combination with the casing having the opening at its top, and the raised platform also 130 having an opening above the first-named opening, of the vertically-movable sleeve on the reverse-switch shaft having a seat for an operating-handle, and also a guard-flange ar-

ranged to close the opening in said casing, and also, in one position of the said sleeve, the opening in said platform, a handle having a flange also arranged to close the opening in the platform in another position of the said sleeve, and means for raising and lowering said sleeve.

5 ranged to detachably engage said sleeve, above said guard-plate, a lever pivoted within said casing and engaging said sleeve, a cam carried by the regulating-switch and impinging said lever to actuate it in one direction, and a spring for actuating said lever in the opposite direction.

10 12. In a controller for electric motors, the combination of a controller-casing, regulating and reverse switches mounted therein, means for operating the regulating-switch, and a guard-plate on the top of the controller-casing, of a vertically-movable sleeve on the shaft of the reverse-switch, a handle ar-

15 In testimony whereof I have affixed my signature in presence of two witnesses.
